UNITED STATES PATENT OFFICE.

CARL C. MOSE, OF CHICAGO, ILLINOIS, ASSIGNOR TO THE STUDEBAKER CORPORATION, OF SOUTH BEND, INDIANA, A CORPORATION OF NEW JERSEY.

DESIGN FOR AN AUTOMOBILE RADIATOR CAP ORNAMENT.

Application filed October 7, 1926. Serial No. 19,269. Term of patent 14 years.

To all whom it may concern:

Be it known that I, CARL C. MOSE, a citizen of the United States of America, and resident of Chicago, in the county of Cook and State of Illinois, have invented a new, original, and ornamental Design for an Automobile Radiator Cap Ornament, of which the following is a specification, reference being had to the accompanying drawing, forming a part thereof.

In the drawing Figure 1 is a side elevation of an automobile radiator cap ornament, and Figure 2 is a side elevation looking from the opposite side from that shown in Figure 1.

I claim:

The ornamental design for an automobile radiator cap ornament as shown.

Signed by me at South Bend, Indiana, this 28th day of September, 1926.

CARL C. MOSE.
